COAXIAL SWITCH

Thomas A. Newkirk, Fairfield, Ohio

Application August 4, 1944, Serial No. 548,122

4 Claims. (Cl. 200—6)

(Granted under the act of March 3, 1883, as
amended April 30, 1928; 370 O. G. 757)

¹ The invention described herein may be manufactured and used by or for the Government for governmental purposes, without the payment to me of any royalty thereon.

The invention to be hereinafter described relates to multiple contact rotary switches for coaxial lines in radio circuits.

It is particularly applicable to radio circuits.

Where a radio circuit conductor is bent or deflected at a sharp angle as is often the case in switching from one part to another of a line or from one line to another line, the resulting reflection is a serious objection. In coaxial lines in radio circuits any bending or deflection is conducive to variation in the surge impedance, as is well known. That is due to the fact that the radial distance between the conductors, in the area of the bend or deflection generally varies. Such variation in surge impedance is a further serious objection in many of the existing switches. A further difficulty with many existing types of multiple contact rotary switches for coaxial lines is that the selected contacts, at any one time or position are not adequately isolated from those not so selected, with resulting uncertainty of and inefficiency in operation.

The main objects of the present invention are to overcome the above and other difficulties and deficiencies and provide a simple, compact, efficient and relatively low cost rotary multiple contact switch, which will selectively make any one of a number of connections, at an angle, between one line and any other given line of a predetermined group or series of lines, minimizing reflection effects and variation in surge impedance and, at the same time, adequately isolating all contacts except those specifically selected.

In order to more clearly disclose the construction, operation and use of the invention reference should be had to the accompanying drawings forming part of the present application.

Throughout the several figures of the drawings like reference characters designate the same parts.

In the drawings—

Fig. 1 is a top plan view;

Fig. 2 is a top plan view with cover plate removed;

Fig. 3 is a side elevation;

Fig. 4 is a central vertical cross section, showing the rotary block in side elevation;

Fig. 5 is a side elevation of one of the matching faces of the rotary block with center conductor in position; and

² Fig. 6 is a fragmentary cross section, enlarged, showing the plunger 22 in side elevation.

While the terms inlet and outlet or input and output are relative to the direction of flow and the direction of flow is not fixed or permanent but may be varied with circumstances, it will be simpler and more convenient to designate the directions of flow in the present application and refer to inlet and outlet relative thereto. Actually they are end or terminal connections, whether inlet end or outlet end.

The casing 1 is, preferably, cylindrical and of brass or other suitable material. Brass is readily machined. It could be of other readily moldable material.

It is provided with a sleeve 2 of standard type to receive the usual electrical connection, the sleeve being mounted centrally in the base of the cylinder. A plurality of standard similar inlet or input connectors 3 are disposed at intervals in the cylinder side wall. For purposes herein-after disclosed, these input connectors are disposed in the same circumferential plane in the cylinder wall.

25 Within the cylinder is revolvably mounted a split block comprising two complementary halves, the matching or cooperating faces being provided with certain bores, channels, grooves, etc., as will hereinafter appear. The split block, as a whole and in assembled relation is rectangular having one dimension corresponding to the inside depth or vertical measurement of casing 1 and a second dimension corresponding to the diameter of casing 1. When positioned, the ends of block 4 will be in free running or sliding contact with the inner wall of casing 1 except as will be herein-after set forth. To give a smoother running fit and continuous bearing between the cylinder wall and the whole adjacent block end, said ends are rounded on the same radius or curvature as that of casing 1. To effect rotation of block 4 a shaft 5 is provided midway of its length, extending laterally of it, and, in assembled position, coincident with the vertical axis or center of casing 1. A

45 simple way to secure this shaft in the block is to provide the two halves with matching shaft grooves 6. When the block halves are secured together by screws 7 or the like they securely clamp shaft 5 so that the block must rotate with the shaft. For easy operation shaft 5 may be provided with a knob or other handle 8. A positive connection may also be provided by a set-screw passed through the block and turned in against the shaft, in well known manner.

55 In order to yieldingly maintain the block in re-

spective selected positions, a small plunger 8 with rounded or inclined operative end is provided. This plunger is mounted in a bore formed by matching grooves 10 in the block halves and is mid-way between the sides of the block. It is urged to operative positions by a compression spring 11 confined between it and the inner end of the bore or assembled grooves. Plunger 8 cooperates with sockets, seats or notches 12 in the cover plate 13.

Centrally seated in block 4 and projecting therefrom is a standard outlet or output connection 14. The outlet connection is also so placed as to constitute the axis of rotation for block 4 and is journaled in the sleeve 2, when the parts are operatively assembled. The matching halves are provided with quadrant or quarter circle grooves, channels, etc., 15 of circular cross section. These grooves extend from the lower edge of the block at its axis of rotation in assembled relation, to a point near its upper edge terminating in its vertical wall or end. In the upper end and extended at right angles to connector 14 is slidably mounted a cylindrical plug or contact 16 having its outer end wall ground to the same arc or curvature as that of the cylinder wall. To maintain 16 in sliding contact with cylinder 1 a coil spring 17 may be used.

Concentrically within the assembled grooves 15 is a central conductor 18 of copper or the like and either tubular or solid, as the case may be. Its ends are seated in insulating sleeves 19, which, in turn, extend into the connector 14 and plug 16. It has been found that the conductor 18 usually, is sufficiently self-sustaining to maintain its curvature and concentric position, after it has once been shaped. In cases where it seems advisable to rely on other means, suitable insulating spacers may be provided at intervals. The block 4 and particularly the concentric groove-wall 15, constitutes the outer conductor of the coaxial circuit. For that purpose, the plug 16, in sliding contact with the block, by spring pressure, is also in sliding contact with the cylinder wall. As the block is rotated, plug 16 will engage the inner wall of the respective input connectors 3, successively establishing electrical connection at each. At the same time, a small radially directed spring pressed plunger 22 in the outer end of center conductor 18 will similarly contact with the center conductor of the respective input connector 3, completing that connection. By having plug 16 and plunger 22 slidably mounted and constantly maintained in wiping contact with cylinder wall, all wear will be automatically taken up and reliable wiping contact will be continuously maintained. A small pin and notch maintain 16 against rotating in its socket so that its outer curved surface will remain in proper free sliding contact.

It will be noticed that the entire inner cylindrical wall of casing 1 is thoroughly electrically insulated as at 20 except at the inputs 3 which extend through the insulations in the path of rotations of the block and its plug.

The end of the block opposite plug 16, is notched as at 23 to provide ample clearance between that end and an input connector while connection is established through the diametrically opposite input connector, as above. This avoids chance of short circuit, as will be clear.

In view of the above description, it will be seen that there can be no short circuiting between the block and cylinder wall and that only one input at any one time can be brought into the circuit,

as the block is rotated, all others being completely isolated.

Since plunger 8 and notches 12 cooperate, the notches are so distributed that they may be aligned with respective planes passing diametrically through casing 1, and, therefore, through the respective axis of one or another of the input connectors 3. So, in assembling, the cover plate 13 is connected to casing 1 with the respective notches 12 properly positioned relatively to the connectors 3. Then rotations of block 4 by shaft 5 will successively complete the circuit through the centrally disposed outlet and the respective inlet 3. As the circuit is completed, plunger 8 will drop into the corresponding notch 12, spring 11 yieldingly maintaining it against accidental rotation of block 4 such as would break the contact.

As a matter of convenience in determining the exact circuit being completed, each input connection may be numbered. Conveniently this number may be placed on the cover plate, where it will be readily seen. A dial plate 21 may be connected, concentrically, to shaft 5 to rotate therewith and provided with an opening 21' placed to fall over the respective numbers as the shaft is rotated so that as block 4 moves to various contact positions the corresponding circuit or cable number will appear through the dial. Of course, a pointer or other device may be similarly used.

It will be noticed that there is no sharp angle in the connection but a gradual, steady and regular curve thereby minimizing to a very great extent all objectionable reflection effects regularly encountered where the connections do include angular changes in direction.

Also, as clearly shown, the central conductor is maintained concentric throughout its length in block 4, relative to the outer coaxial conductor. At no point in its length does it assume any eccentricity relative to the outer coaxial conductor. This, as previously indicated, greatly minimizes variation in surge impedance.

The two complementary block halves or sections may be separably connected in any suitable and well known manner. Here it has been shown as screws, but it will be well understood that any other practical means may be used.

It is thought that the construction, operation and use of the invention will be clear from the preceding detailed description.

Changes may be made in the construction, arrangement and disposition of the various parts of the invention within the scope of the appended claims without departing from the field of the invention, and it is meant to include all such within this application wherein only one preferred form has been illustrated, purely by way of example and with no thought of, in any degree, limiting this invention thereby.

Having thus described my invention, what I claim and desire to protect by Letters Patent is:

1. A multiple contact rotary switch of the character described comprising a cylinder provided with an axially disposed opening through its base and a plurality of coaxial terminal connectors comprising central conductors and disposed in the same circumferential plane in its side wall and each disposed approximately at right angles to the aforesaid axially disposed opening in a plane parallel to the cylinder axis, a block rotatably mounted within said cylinder and extending diametrically across the interior of said cylinder, said block comprising a pair of complementary plates each having a quarter-

circle channel so extending in one continuous curve from one end of the axis of rotation to a point adjacent a diagonally opposite corner, that said channels, in assembled relation, may be brought into registration with the aforesaid axially disposed opening and a predetermined coaxial terminal connector, a conductor within said channel to contact the predetermined coaxial terminal conductor, and means automatically, yieldingly retaining said block in respective selected position.

2. A multiple contact rotary switch of the character described comprising a cylinder provided with an axially disposed opening through its base and a plurality of coaxial terminal connectors comprising central conductors and disposed in the same circumferential plane in its side wall and each disposed approximately at right angles to the aforesaid axially disposed opening in a plane parallel to the cylinder axis, a block rotatably mounted within said cylinder and extending diametrically across the interior of said cylinder, said block comprising a pair of complementary plates each having a quarter-circle channel so extending in one continuous curve from one end of the axis of rotation to a point adjacent a diagonally opposite corner, that said channels, in assembled relation, may be brought into registration with the aforesaid axially disposed opening and a predetermined coaxial terminal connector, a conductor within said channel to contact the predetermined coaxial terminal conductor, a contact plunger yieldingly carried by said conductor and means maintaining said plunger in wiping contact with said cylinder during rotation of said block.

3. A multiple contact rotary switch of the character described comprising a cylinder provided with an axially disposed opening through its base and a plurality of coaxial terminal connectors comprising central conductors and disposed in the same circumferential plane in its side wall and each disposed approximately at right angles to the aforesaid axially disposed opening in a plane parallel to the cylinder axis, a block rotatably mounted within said cylinder and extending diametrically across the interior of said cylinder, said block comprising a pair of complementary plates each having a quarter-circle channel so extending in one continuous

curve from one end of the axis of rotation to a point adjacent a diagonally opposite corner, that said channels, in assembled relation, may be brought into registration with the aforesaid axially disposed opening and a predetermined coaxial terminal connector, a conductor within said channel to contact the predetermined coaxial terminal conductor, means automatically, yieldingly retaining said block in respective selected position, a contact plunger yieldingly carried by said conductor and means maintaining said plunger in wiping contact with said cylinder during rotation of said block.

4. A multiple contact rotary switch of the character described comprising a cylinder provided with an axially disposed opening through its base and a plurality of coaxial terminal connectors equidistantly disposed in the same circumferential plane in its side wall and each disposed approximately at right angles to the aforesaid axially disposed opening in a plane parallel to the cylinder axis, a conducting block rotatably mounted within said cylinder and extending diametrically across the interior of said cylinder, said block being provided with a cylindrical channel extending in one continuous quarter-circle curve from one end of the axis of rotation to a point adjacent a diagonally opposite corner, so that said channel may be brought into registration with the aforesaid axially disposed opening and a predetermined coaxial terminal connector, a conductor centrally disposed longitudinally of said channel, a conducting plug slidably mounted in one end of said channel in contact with said block and insulated from said conductor and in sliding contact with said coaxial terminals, a contact plunger yieldingly carried by said conductor and insulated from said block and means maintaining said plunger in wiping contact with the aforesaid coaxial terminals during rotation of said block.
